UNITED STATES PATENT OFFICE

PHILIP J. BUEHLER, OF HOKAH, MINNESOTA

EXPANSIBLE PARTING STRIP

Application filed May 14, 1930. Serial No. 452,472.

This invention relates to a combined parting and weather strip and window sash holder.

One of the objects of the invention is the provision of an expansible or resilient parting strip capable of being applied in a novel manner and adapted to effectively exclude the elements of weather, also to hold sashes in different positions, and also to prevent the

10 sashes from rattling.

Another object of the invention is the provision of a parting strip construction made of metal parts which may be readily assembled and attached to a window frame, for the purpose of maintaining a sealing contact along the side of a sash, and also adjustable to compensate for wear.

With the foregoing and other objects in view, the invention resides in the particular provision, combination, construction and function of the parts hereinafter fully described and illustrated in the accompanying drawings, in which

Figure 1 is a side view of a window frame and sashes selected to illustrate the invention which is shown applied thereto;

Figure 2 is an enlarged section taken on the line 2—2 of Figure 1;

Figure 3 is a fragmentary perspective view 30 of the parting strip;

Figure 4 is a fragmentary perspective view of the wedge member;

Figure 5 is a fragmentary perspective view 35 of the base part;

Figure 6 is a fragmentary section showing a portion of a window frame and portions of the parting strip assemblages as applied to the head rail and side stile of the frame and illustrating the manner of joining them at 40 the corner of the frame.

Referring now more particularly to the several views of the drawings, it will be apparent that there is shown in window frame 10 and sashes 11 arranged for up and down movement in said frame. In the present instance each of the side stiles 12 of the frame and the head rail 13 has a groove 14 therein, the grooves in these parts being in continuation of each other.

50 In accordance with the invention there is

provided for association with each stile 12 and the head rail 13 a parting strip 15, a base part 16, and a wedge member 17. The strip 15 is made of a piece of spring sheet bronze bent and formed to provide portions 55 18 united by a connecting portion 19. It will therefore be apparent that the strip 15 is substantially of U-shape in cross section. The free edges of the portions 18 are curled as at 20. The portions 18 are capable of flexing laterally due to the inherent springiness of the metal. The portion 19 is provided with a plurality of holes 21. The base part 16 is made of sheet galvanized metal bent 60 in form to present portions 22 each having a flange 23 along one edge, and a connecting portion 24 which unites the flange of one portion 22 with the flange of the other portion 22. The free edge of each portion 22 is curled outwardly to provide a bead 25. The portions 22 will be laterally flexible toward 65 and away from each other by reason of the springiness of the metal. The connecting portion 24 has a plurality of holes 26 equal in number to the number of holes 21 in the connecting portion 19 of the strip 15. The wedge member 17 is made of a piece of galvanized metal which is bent into the form of a channel concavo-convex in cross section. The wedge member 17 has a plurality of holes 70 or slots 27 therein equal in number to the number of holes 21 in the portion 19 of the strip 15. The base part 16 and the wedge member 17 are approximately equal in length, and both are slightly longer than the parting 75 strip 15 in order to accommodate a corner part 28 which is made of a piece of bronze or brass of substantially U-shape in diagonal section, and presenting end edges 29 which are receivable respectively in the upper end 80 of the parting strip 15 arranged on the side stile 12 and the adjacent end of the parting strip 15 arranged on the head rail 13, it being understood that a similar part 28 will be provided at each of the upper corners of the 85 window frame 10.

A parting strip 15, a base part 16 and a wedge member 17 assembled will be secured in place to the related side stile 12 or head rail 13, as the case may be. The base part 100

16 will be arranged in a groove 14 and be temporarily held in place by small nails or tacks driven through the connecting portion 19 into the frame 10, as shown in Figures 6, 5 one of the nails being indicated at 30. The wedge member 17 is then arranged between the free curled edges of the portions 22 of the base part 16 with the concavo-convex surface of the wedge member 17 in contact with 10 the curled edges of the portions 22. The parting strip 15 is then associated with the base part 16 and the wedge member 17 with the flexible portions 18 of the strip 15 disposed adjacent the flexible portions 22 of the 15 base part 16. Use is made of fastening elements such as screws 31 which are received respectively in the alined holes 21, 26 and 27, in the strip 15, base part 16 and wedge member 17; the said screws 31 being driven into 20 the frame 10. It will therefore be understood that the screws 31 exert pressure on the parting strip 15 causing the latter to exert pressure on the wedge member 17, also causing the wedge member 17 to exert 25 pressure on the flexible portions 22 of the base part to exert pressure on the portions 18 of the parting strip. The portions 18 of the parting strip will be flexed laterally away from each other and will be disposed to 30 engage the confronting sides of the sashes 11 in sealing and frictional contact therewith. It will be obvious that by adjusting the screws 31 more or less pressure will be exerted on the flexible sash engaging portions 35 18 of the parting strip 15. It will therefore be understood that the parting strip 15 is adapted to exclude the elements of weather, is also adapted to hold the sashes 11 in different positions in the frame 10, and is also 40 adapted to prevent the sashes 11 from rattling. Furthermore, the strip 15 will compensate for any wear on the sashes 11 which will not be very great. The parting strip 15 applied to the head rail 13 of the frame 10 45 will function for the intended purpose in conjunction with the top member of the upper sash 11. It is to be understood that the groove 14 is not necessary and that the parting strip construction can be used on any 50 standard window without altering either the frame or the sashes.

Claims:

1. The combination with a window frame and sashes arranged for movement in said 55 frame, of a parting strip secured to the frame between the sashes, said strip having flexible portions, flexible strips suitably united adjacent said flexible portions, and means to exert pressure on said strips to cause them 60 to exert pressure on said flexible portions to maintain said flexible portions under tension to frictionally engage the sides of said sashes.

2. The combination with a window frame 65 having a groove therein, of a base part ar-

ranged in said groove and having laterally flexible portions projecting from said groove, a parting strip having laterally flexible sash engaging portions, a wedge member, said base part, parting strip and wedge member being 70 assembled so that the parting strip will exert pressure on the wedge member causing the wedge member to exert pressure on the flexible portions of the base part and also causing the flexible portions of the base part to exert 75 pressure on the sash engaging portions of the parting strip, and means which secures said base part, wedge member and parting strip to the frame and which also exerts pressure 80 on said parting strip.

3. The combination with a window frame and sashes arranged in the frame for movement with respect thereto, of a parting strip secured to the frame between the sashes, said strip having flexible side portions each 85 extending the entire length of the strip, and means including a wedge to maintain said flexible portions under tension to frictionally engage the sides of said sashes respectively.

4. The combination with a window frame and sashes arranged for movement in said frame, of a parting strip secured to the frame between the sashes, said strip having flexible portions, expansible means adapted to exert 95 pressure on said flexible portions to maintain said flexible portions under tension to frictionally engage the sides of said sashes, and separate means adapted to expand said 100 expansible means to cause it to exert the desired degree of pressure on said flexible portions.

5. The combination with a window frame and sashes arranged for movement in said frame, of a parting strip secured to the frame 105 between the sashes, said strip having flexible portions, and expansible means to maintain said flexible portions under tension to frictionally engage the sides of said sashes, said 110 expansible means including flexible portions respectively in contact with the first mentioned flexible portions the entire length thereof.

6. The combination with a window frame having a groove extending longitudinally in a section thereof, a base part extending in said groove approximately throughout the length thereof and having spaced longitudinal flexible portions which project from the groove, a weather part equal in length to the base part and having spaced longitudinal flexible portions which overlap the first mentioned flexible portions, an expander between the flexible portions on the base part and the weather part, and fastening elements extending through the base part, expander and weather part and screwed into said frame section and exerting pressure on the weather part, whereby the flexible portions of the weather part will be maintained 115 120 125 130 135 140 145 150

under the desired degree of tension to serve as a sealing strip.

7. A weathering structure comprising a base part constructed of a single piece of sheet metal substantially U-shape in cross section to present spaced elongated flexible portions; a wedge constructed of a single piece of sheet metal, a weather part constructed of a single piece of sheet metal substantially U-shape in cross section to present spaced elongated flexible contact portions, the base part, wedge and weather part being assembled so that the flexible portions of the base part will be in contact with the flexible portions of the weather part and the wedge will be in contact with the flexible portions of the base part and the weather part will be in contact with the wedge, and means to secure said parts in place and also to exert pressure on the wedge to maintain said flexible portions under tension.

8. A weathering structure comprising three principal parts of approximately equal length, each part being made of metal, two of said parts having flexible portions in contact with each other and the third part being in the form of a wedge and disposed between the other two parts to coact therewith and adapted to maintain said flexible portions under tension, the flexible portions of one part constituting means to effect sealing contact with structural units, and means common to all of the parts for securing them in place and to exert pressure on one part to cause it to exert pressure on the wedge to maintain said flexible portions under tension.

9. A weathering structure comprising a weather part having integral flexible strip members, and expansible means adapted to maintain said strip members under tension.

10. A weathering structure comprising a weather part having integral flexible strip members, a base part having integral flexible pressure strip members arranged between said first mentioned strip members, a part adapted to be arranged between said second strip members to exert pressure thereon to cause them to exert pressure on said first strip members to maintain the latter under tension, and means to retain said parts in assembled relationship.

11. A weathering structure comprising a weather part constructed of sheet metal and of U-shape in cross section to provide flexible strip members, a base part constructed of sheet metal and of U-shape in cross section to provide flexible pressure strip members, said base part being capable of being arranged between the strip members of the weather part with its strip members in contact with the former, apart approximately equal in length to the strip members of the base part adapted to be arranged between them to exert pressure thereon to cause them

to exert pressure on the strip members of the weather part to maintain them under tension, and securing means to retain said parts in assembled relationship.
